CLAIM

The ornamental design for a front bumper lower cover for an automobile, as shown and described.

DESCRIPTION

1. Front bumper lower cover for an automobile
- 1.1 is a front and left side perspective view of a front bumper lower cover for an automobile embodying our new design;
- 1.2 is a front elevation view thereof;
- 1.3 is a rear elevation view thereof;
- 1.4 is a right side elevation view thereof;
- 1.5 is a left side view thereof;
- 1.6 is a top plan view thereof;
- 1.7 is a bottom plan view thereof;
- 1.8 is a bottom, front, and left side perspective view thereof; and
- 1.9 is a top, rear, and left side perspective view thereof.
